UNITED STATES PATENT OFFICE.

JAKUB NAGRABSKI, OF WATERBURY, CONNECTICUT.

CLOTHES-HANGER.

1,308,605.

Specification of Letters Patent.

Patented July 1, 1919.

Application filed May 9, 1919. Serial No. 295,939.

To all whom it may concern:

Be it known that I, JAKUB NAGRABSKI, a citizen of Poland, residing at Waterbury, in the county of New Haven and State of Connecticut, have invented certain new and useful Improvements in Clothes-Hangers, of which the following is a specification.

The primary object of this invention is to provide a combined coat and trousers hanger with novel trousers clamping bars and an improved form of hanger hook carried by the coat hanging portion thereof.

With the above general object in view and others that will become apparent as the nature of the invention is better understood, the same consists in the novel form, combination and arrangement of parts herein-after more fully described and shown in the accompanying drawing, in which like reference characters indicate corresponding parts throughout the several views.

In the drawing,

Figure 1 is a front elevational view of a combined coat and trousers hanger constructed in accordance with the present invention,

Fig. 2 is a top plan view thereof,

Fig. 3 is an end elevational view,

Fig. 4 is a cross sectional view taken vertically through the hanger portion and

Fig. 5 is an enlarged fragmentary perspective view of a portion of the trousers hanger element.

Describing the invention more in detail, there is provided a curved bar 6 of the usual form and corresponding in a general way to the curvature of the shoulders of a coat having trousers clamping bars 7 depending therefrom and a hanging hook 8 secured centrally thereof for suspending the same.

The suspending hook is formed of resilient wire and includes a substantially circular portion 9 having a terminal knob 10 that is engaged by the bent portion 11 of the opposite end, further resiliency being given to the bent portion by a tortuous bending 12. Extending forwardly of the hanger 8 are integrally formed members 13 and 14, the member 14 constituting a garment supporting hook while the member 13 has a downwardly bent hook portion at its free end and constituting a keeper for the hook to prevent accidental displacement of the garment placed therein.

At suitable points, equi-distantly spaced

and upon opposite sides of the suspending hook 8 and upon the free face of the hanger bar 6 are eye-bolts 15 to each of which is connected a suspending ring 16 that carries a pair of rings 17 to which are connected the trousers clamping bar supporting arms 18, said arms 18 having the trousers clamping bars 7 fixed to the lower ends thereof. The arms 18 are provided midway the ends thereof with corresponding outwardly curved portions 19 between which a retractile coil spring 20 is connected so that the trousers clamping bars 7 are held in adjacent position at all times. As more clearly shown in Fig. 5, the adjacent faces of the clamping bars 7 are provided with a felt or similar surface material 21 which directly engages the lower ends of the trousers 22 when in inverted hanging position.

From the above detailed description of the invention, it is thought that the construction and operation thereof will be at once apparent, it being noted, however, that the resilient engaging point between the two ends of the suspending hook 8 will prevent accidental displacement of the hanger from its support until forcibly removed by the user of the device. The trousers clamping bars 7 or the arms 18 may be gripped by the hands of the user and the trousers ends inserted between the clamping bars 7 and upon pressure thereon being released whereby the springs 20 will exert their force and draw the bars into closed relationship thereby to clamp the trousers in set position as shown in Fig. 5, at which time a waistcoat and top coat may be mounted upon the bar 6 and any articles desired suspended upon the hook 14.

What I claim as new is:

1. A device of the class described comprising a curved coat hanging bar, a suspending hook carried thereby, said hook having resiliently engaging ends forming an entrance opening to the suspending hook portion, eye-bolts carried by the under face of said bar, a ring secured in each eye-bolt, a pair of rings secured in the aforesaid ring, a pair of depending arms secured in the last named rings, trousers clamping bars carried by the lower ends of said arms and a spring extending between said arms adapted to hold the trousers clamping bars in adjacent position.

2. A device of the class described com-

2
prising a coat hanger arm, a suspending hook carried thereby, said hook having resiliently engaging ends controlling entrance to the suspending portion thereof, a pair of arms loosely suspended from said bar, said arms having corresponding outwardly curved portions, trousers clamping bars se-

cured to the lower ends thereof and retractile coil springs connected at their ends to the outwardly curved portions of the arms 10 tending normally to maintain the trousers clamping bars in adjacent position.

In testimony whereof I affix my signature.
JAKUB NAGRABSKI.
